(57) **CLAIM**

I claim the ornamental design for a child's novelty bank, as shown and described.

DESCRIPTION

FIG. 1 is a side perspective view of a child's novelty bank;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The broken lines illustrate portions of the child's novelty bank which form no part of the claimed design.
